(57) **CLAIM**

The ornamental design for a display screen or portion thereof with graphical user interface for automobile air-conditioning control, as shown and described.

DESCRIPTION

The FIGURE is a front view of a “display screen or portion thereof with graphical user interface for automobile air-conditioning control” showing our new design.

The evenly spaced broken line illustrating a display screen and the unevenly spaced broken line illustrating the boundary of the claim form no part of the claim. The faded portions within broken lines form no part of the claim.

In the drawings, the portion of a display screen or portion thereof with graphical user interface for automobile air-conditioning control shown in lighter gray scale represents environmental subject matter that forms no part of the claimed design.
